UNITED STATES PATENT OFFICE.

HENRY LEITNER, OF WESTMINSTER, LONDON, ENGLAND.

SCREW-PROPELLER.

1,328,005.

Specification of Letters Patent. Patented Jan. 13, 1920.

Application filed March 25, 1919. Serial No. 285,051.

To all whom it may concern:

Be it known that I, HENRY LEITNER, a subject of the King of Great Britain, residing at 3 Victoria street, Westminster, London, England, have invented new and useful Improvements in Screw-Propellers, of which the following is a specification.

My invention relates to screw propellers, chiefly designed for use with air-craft, and 10 to that class of propeller in which the blades are hollow, and are made of sheet metal plates welded or otherwise suitably joined at the edges.

The object of my invention is to improve 15 the construction of propellers of this type, and more particularly that part of the propeller comprising the hub and adjacent parts of the blades where the stress is greatest.

20 To this end, according to my invention, I make the blades of sheet-metal rolled, stamped, or otherwise shaped to the required thickness and form, the two faces of the said blades being formed from separate 25 sheets, the edges of which are welded or otherwise suitably united. Within the outer sheath, and more particularly in that part surrounding the hub and adjacent thereto, I provide a sheet metal liner or lamina, or 30 a number of sheet metal liners or laminae, stamped or otherwise formed from a blank to conform with the shape of the outer sheath. The outer sheath and liner or liners are secured to a hub comprising a central 35 tube adapted to fit the driving shaft and provided with shaped end driving plates which may be wholly or approximately flat, and are preferably partially circular in outline for a short distance only on each side of 40 a given diameter line. In two opposite directions, and approximately at right angles to this diameter line, the plates are formed with extensions or "horns," which may either be flat or shaped to the curve which 45 is usually given to a propeller blade where it joins the central boss. These "horns" are of such a shape that their edges correspond with the edges of the stamped or shaped sheet metal forming the blades. The end 50 plates may further and advantageously be provided with a shoulder, or bead on their edges, or with a bead ridge or groove on their inside faces, on which to rest the edges of the sheet metal forming the blades and 55 the laminae. Such a construction enables the sheet metal to have a long solid edge to

which it can be welded, and to be practically without the filling-in pieces which would otherwise be required. Much greater strength is thus obtained at their junction with the 60 hub. A propeller constructed in this manner could be driven at a moderate speed without any welding or other attachment of the plates to the hub. This of course is not advisable, but it serves to show the greatly 65 improved construction whereby much of the strain is taken off the welded joints.

To increase the rigidity or stiffness of the blade internal ribs and transverse gage or distance pieces may be provided, the former 70 being advantageously made integral with the liners and the latter separate pieces suitably secured to the sheaths.

To enable my invention to be fully understood I will describe it by reference to the 75 accompanying drawings, in which;

Figure 1 is an elevation of one form of propeller constructed according to my invention.

Fig. 2 is a sectional elevation, and 80

Fig. 3 is a sectional plan of the same.

Figs. 4, 5, 6 and 7 are respectively sections on the lines 4—4, 5—5, 6—6 and 7—7, Fig. 1.

Fig. 8 is a view of a detail of the construction illustrated in Fig. 7. 85

Fig. 9 is an elevation of the boss or hub of the propeller, and

Fig. 10 is a plan thereof.

Figs. 11 and 12 are views similar to Fig. 90 2, illustrating modifications.

Fig. 13 is a section on the line 13—13, Fig. 12, and

Fig. 14 is a detail of the construction 95 illustrated in Fig. 13.

Referring to Figs. 1 to 10, *a* is the outer sheath of the propeller and *b* the liners or laminae of different lengths fitting within the same and within one another, as shown clearly in Figs. 2 and 3. *c* is the central 100 tube of the boss or hub having the flanges or end plates *d*. In this form of propeller the sheath *a* and the laminae are shaped to fit between the flanges *d*, the latter being rabbed or recessed at *d*² to receive them, as 105 shown clearly in Fig. 4. The sheath *a* and laminae *b* are bent to the required form and welded or otherwise connected together at their edges as indicated in Fig. 6. The dotted lines at *d*², Fig. 4 indicate grooves which 110 may be provided for lightening the structure.

e, e are the horns or extensions on the hub flanges *d* designed to fill the spaces formed between the edges of the sheath *a* and laminæ *b* where they separate to pass around 5 the hub on opposite sides, which spaces would ordinarily require to be filled by separate filling pieces. These horns are formed with beveled surfaces *f* to which the edges of the sheath *a* and laminæ are 10 welded or otherwise attached, the said surface merging into the rabbets *d¹*.

g, Figs. 7 and 8, indicates one of the gage or distance pieces between the walls of the sheath *a* for stiffening or constructional purposes, and *h, i* are lugs formed thereon in pairs. The lugs *h* when bent at right angles to the body of the gage piece, as indicated by the dotted lines in Fig. 8, serving for attachment to the edges of the plates forming 15 the sheath by welding or otherwise, while the lugs *i* can be also bent at right angles and attached to the sheath by spot welding, or passed through holes in the latter and riveted or welded as indicated. These gage 20 pieces, either with or without the lugs, may be welded inside one blade of the sheath before the blades are put together, or they may be welded on to the ends of the laminæ, or the end of a lamina may have an extended 25 strip or strips to which a gage piece or pieces is or are fixed.

Fig. 11 shows a construction wherein the laminæ or liners *b*, of which two pairs are shown, do not follow the contour of the 30 sheath *a*, as in Fig. 2, but cross the hub in a more direct line, and form, as it were, ties between the two blades, and a kind of cellular structure as above referred to. Their edges are preferably welded to the end 35 plates or flanges of the hub where they cross the latter. In a further modification instead of bringing the laminæ across the hub, the sheath *a* may be so arranged, and the laminæ caused to follow the outer contour, 40 but this is not so advantageous.

In the construction illustrated in Figs. 12, 13 and 14, a single pair of laminæ is shown having ribs *j* formed or pressed in them to 45 stiffen them. The opposed ribs abut, as shown, and may be welded or otherwise attached together.

It is obvious that the construction or constructions hereinbefore described are equally applicable to either three-bladed or four-bladed propellers. The laminæ will in each case pass across the hub from the inner portion of one blade to the corresponding inner portion of the next adjacent blade. The number of "horns" of the improved hub will be correspondingly increased. 55

I do not limit myself to the particular shape or design of propellers as shown in the drawing nor to the arrangement of parts in the particular manner herein illustrated and described, since it is obvious that many 60 variations and modifications may be used without departing from the scope of the invention.

Having now particularly described and ascertained the nature of my said invention 70 and in what manner the same is to be performed, I declare that what I claim is:—

1. A screw propeller comprising hollow blades formed of a sheet metal sheath having gaps adjacent the hub in combination 75 with a hub composed of a central tube and end plates having horns forming power transmitting filling pieces for the gaps in the sheath adjacent to the hub, substantially as hereinbefore described.

2. A screw propeller comprising hollow blades formed of an outer sheet metal sheath having gaps adjacent the hub with an internal laminal strengthening adjacent to the hub in combination with a hub composed of 85 a central tube and end plates having horns forming power transmitting filling pieces for the gaps in the sheath adjacent to the hub, substantially as described.

3. A screw propeller comprising hollow 90 blades formed of an outer sheet metal sheath having gaps adjacent to the hub, with an internal laminal strengthening adjacent to the hub and internal transverse strengthening members, in combination with a hub composed of a central tube and end plates having horns forming power transmitting filling pieces for the gaps in the sheaths adjacent to the hub, substantially as hereinbefore described.

HENRY LEITNER.
